UNITED STATES PATENT OFFICE.

HOOD PITTS, OF AUSTIN, TEXAS, ASSIGNOR OF ONE-HALF TO FRANK M. COVERT, OF AUSTIN, TEXAS.

FLOOR SELECTOR-SWITCH FOR ELECTRIC DOOR-OPERATING APPARATUS.

1,139,902.

Specification of Letters Patent.

Patented May 18, 1915.

Application filed December 24, 1912. Serial No. 738,494.

To all whom it may concern:

Be it known that I, Hood Pitts, a citizen of the United States, residing at Austin, in the county of Travis and State of Texas, have invented certain new and useful Improvements in Floor Selector-Switches for Electric Door-Operating Apparatus, of which the following is a specification, reference being had to the accompanying drawings.

This invention relates to a floor selector switch which is designed for use in connection with the electrically controlled door or gate operating means for elevators of that character shown and described in my co-pending applications filed Dec. 24, 1912, Ser. No. 738,495, and Jan. 11, 1913, Ser. No. 741,604.

The present invention has for its primary object to provide a switch arranged at the floor or landing adjacent the elevator shaft normally acting to close the circuit of the door or gate operating means to move the door to its closed position, and means carried by the car for actuating said switch to reverse the operating means and move the door to its open position.

Another object of the invention resides in the provision of means controlled by the operator of the car for actuating the switch to open the door or gate, said means including an electro-magnet, said switch embodying means for placing the same in its normal condition to close the door or gate in the event that the car operator inadvertently neglects to energize the magnet and the car moves away from the floor or landing.

Still another object of the invention is to produce a switch of the above character and cut out devices located in the circuit whereby the locking of the elevator door or gate will be insured and liability of accident by the gate being manually opened thereby obviated.

A still further object of the invention is to produce a floor selector switch for use in connection with apparatus of the above character which is comparatively simple and extremely durable in its construction, may be produced at small cost and effects the noiseless and rapid operation of the elevator doors or gates.

With the above and other objects in view as will become apparent as the description proceeds, the invention consists in certain

constructions, combinations and arrangements of the parts that I shall hereinafter fully describe and claim.

For a full understanding of the invention, reference is to be had to the following description and accompanying drawings, in which—

Figure 1 is a view illustrating a portion of an elevator car or cage and a shaft door or gate with its operating mechanism, my improved switch and the operating circuit being diagrammatically illustrated; Fig. 2 is an enlarged vertical section of the floor selector switch embodying the present improvements; Fig. 3 is a side elevation thereof; Fig. 4 is a top plan view; and Fig. 5 is a perspective view of the movable contact carrying arm.

Referring in detail to the drawings, 5 designates an elevator car of any approved form and construction and 6 indicates a portion of one of the shaft gates or doors. This gate is operated through the medium of motor driven mechanism 7 and in the electric circuit for this motor, to be later described, cut out devices 8 and 9 are arranged to cut the motor out of the circuit and stop its operation at the end of the opening and closing movements of the door or gate. Each of these cut out devices includes stationary and movable contact elements.

An electromagnet 10 is carried by the elevator car, said magnet being supplied with current from the car lighting circuit or other suitable supply source indicated by the numeral 11. In this circuit, a suitable operator's switch 12 is arranged to open the circuit when the car is started and close the same through the electromagnet 10, when the car is stopped.

At each of the floor landings, a reversible selector switch is arranged in the circuit for the gate or door operating means. The subject matter of this application is confined to an improved form of this switch whereby the operating circuit is closed to reverse the motor of the door or gate operating mechanism to move the gate to its open or closed position. To this end, I provide an angular supporting bracket 13, the base of which is bolted or otherwise rigidly secured as shown at 14, to the wall of the elevator shaft. An arm 15 of the bracket plate 13 supports the movable elements of the switch. In the extremity of this arm, a rod or shaft 16 is

5 mounted to rotate and a similar shaft 17 is also rotatably mounted in the inner end of said arm, and is disposed in parallel relation to the shaft 16. The extremities of the
 10 shafts 16 and 17 are connected by means of the links 18 and 19, respectively, to the opposite ends of an armature plate 20. A lug 21 is formed upon the arm 15 of the supporting bracket and in this lug an adjustable stop bolt 22 is threaded. This bolt
 15 limits the movement of the armature plate 20 toward the electromagnet 10 when the same is energized so that said plate will not engage the magnet or project into the path of movement of the elevator car.

Upon the opposite edges of the arm 15 of the bracket the parallel laterally extending plates 23 are formed. These plates are connected by or have integrally formed there-
 20 with the spaced parallel plates 24. In these latter plates, the opposed series of contact members 25, 25^a, 25^b, 25^c and 26, 26^a, 26^b, 26^c, respectively, are movably mounted in suitable insulating blocks arranged in the plates
 25 24, said contact members being yieldingly supported or cushioned by means of the coil springs 27 arranged upon the shanks or studs 28 of said members which are movable through apertures in the plates 24. A mov-
 30 able arm 29 is located between the opposed series of contact members. This arm is provided at one of its ends with a yoke 30, the extremities of which extend upon opposite sides of the bracket and are suitably se-
 35 cured upon the shaft 16. Upon the other end of the arm 29, the spaced contact members 31, 31^a are arranged and suitably insulated from the arm 29. The member 31 is adapted to alternately engage the contacts
 40 25—25^a or 26—26^a, and the member 31^a is adapted to likewise engage the contacts 25^b—25^c or 26^b—26^c in the different positions of the arm 29 to be later described, so as to close the circuit and operate the motor for
 45 the door actuating mechanism in one direction and close the door or reverse the operation of the motor to open the door. In order to hold this contact carrying arm normally in position to close the operating circuit for
 50 the closing movement of the door, I provide a heavy coil spring 32 bearing at one of its ends against a suitable seat provided upon the arm 29. The other end of this spring is connected to a bolt 33 threaded in one of
 55 the plates 24 whereby the compression of said spring may be readily adjusted.

Referring now to Fig. 1 of the drawings wherein I have shown the operating circuit for the door actuating mechanism, it will be observed that the stationary members of the contacts 8 and 9 of the cut out devices are connected to the contacts 25^c and 25 respectively by means of the wires 34 and 34'. 36 indicates the generator or other electric sup-
 60 ply source which is connected by means of

the wire 37 to the contact member 25^c. A pair of current conducting wires 38, 38' are connected to contacts 25^c and 26^c respectively and to the operating motor, and a wire 39 for the reversal of the motor is connected 70 to the contact member 26^c. A return wire 40 is connected to the current supply source 36 and to the magnet of an electric brake arranged upon the motor shaft, the other terminal of the electromagnet being connected 75 by means of the wire 41 to the motor.

In the circuit 11 is placed an operator's switch having two contacts, one of which is a spring arm actuated to normally hold the circuit open. When the car arrives at a 80 landing and the operator's controller lever is thrown to a position to bring the car to rest, the controller handle is pushed into such a position that the spring arm of the switch is moved to complete the circuit 11 85 and the door is moved to its open position. When the car is to be started the first movement of the operator will be to pull the handle from the switch casing so that the lever may be swung. This movement will release 90 the spring arm contact of the switch and the circuit 11 will be broken and the door will be automatically closed. The lever is now free to be swung to start the car.

The details of this switch are not claimed 95 herein, but are made the subject of my pending application for patent filed December 24, 1912, and numbered serially 738,495, above referred to.

By means of this arrangement of the circuit, it will be seen that when the elevator car reaches the landing, and the operator brings the controller lever to the position to stop the car, the lever handle will engage the contacts to complete the circuit to energize the magnet 10, the armature plate 20 is attracted thereby so as to move the contact members 31 and 31^a on the arm 29 into engagement with the series of contact members 25, 25^a, 25^b and 25^c. 100 105 110

As soon as the operator of the car moves his switch to deenergize the magnet 10 or starts the car so as to move the magnet 10 away from the armature plate 20, the spring 32 acting against the arm 29 overcomes the 115 weight of the armature plate and forces the contact members 31 and 31^a carried by arm 29 into engagement with the contacts 26, 26^a, 26^b and 26^c. It is understood, of course, that when the gate is moved to its full open position the circuit is broken through the cut out 8. The return of the contacts 31 and 31^a on the arm 29 to their normal positions in engagement with the contacts 26, 26^a, 26^b and 26^c closes the circuit through the cut 120 125 out 8.

With the door in its open position as shown in Fig. 1, the first movement to start the car will be to throw the switch 12. This will deenergize the magnet 10 and the spring 130

32 will throw the arm 29 and cause the member 31 to bridge the contacts 26 and 26^a and cause the member 31^a to bridge the contacts 26^b and 26^c. The current will now flow as follows, from source 36 through wire 37, contact 25^c, wire 34, cut out 8, wire 34', contact 26, member 31, contact 26^a, wire 38, which includes contact 25^a, armature of motor 7, wire 38' which includes contact 25^b, contact 26^b, member 31^a, contact 26^c, wire 39, field coils of motor 7, wire 41, brake solenoid, wire 40 to source 36, and close the door.

In case the operation of the switch 12 fails, for any reason, to deenergize the magnet 10, the movement of the car will remove the magnet from its armature, the spring 32 will throw the arm 29 and the circuit, as traced, will be made. As the door approaches its closed position the cam on the left of the screw will engage the roller on the movable element of the cut out 8 and break the circuit at that point, but as a circuit has previously been made by the movable element of the cut out 9, when the cam at the right hand end of the screw leaves it, the door will continue to the full extent of its closing movement.

When the car returns to the position shown in Fig. 1, or another car reaches the switch, the magnet 10 will attract the armature 20 against the spring 32 and the arm will be thrown to the position shown. The current will now flow from the source 36 through wire 37, contact 25^c, member 31^a, contact 25^b, wire 38', armature (in reverse direction) wire 38, contact 25^a, member 31, contact 25, wire 34^a, cut out 9, wire 35, contact 26^c, wire 39, field of motor, wire 41, brake solenoid, wire 40 to source, and open the door.

From the foregoing, it is believed that the construction and manner of operation of my improved floor selector switch for elevator door operating apparatus will be clearly understood. It will be apparent that as the operation of the gate is electrically controlled, the same cannot be manually moved from its open or closed positions. By means of my improved switch, even if the car operator neglects to deenergize the magnet 10 and starts the car, the movable arm 29 will, nevertheless, be thrown to engage the contacts thereon with the contacts 26, 26^a, 26^b and 26^c and effect the closing movement of the gate when the magnet on the car moves away from the armature plate 20. It will also be appreciated that by means of a switch constructed in the manner above described, the operator is relieved of much manual labor incident to the opening and closing of the elevator doors or gates and liability of accident and serious injury to persons often due to the fact that the gates are negligently left open by the operator, is entirely obviated.

As my improved switch comprises but few

elements which are of simple form, it will be obvious that the same can be produced at small cost and is not liable to become easily broken and will therefore require but few and infrequent repairs. It will be obvious that the invention is not limited in its practical application to the specific combination and arrangement of the several parts as disclosed in the accompanying drawings, as many minor alterations in the form, construction and proportion of the several elements may be necessitated by special circumstances due to differences in elevator constructions. I, therefore, do not wish to be limited to the precise construction of the device hereinbefore specified but reserve the right to make such modifications therein as may fairly fall within the scope of the appended claims.

Having thus described the invention, what is claimed is:

1. The combination with elevator door operating means and an electric circuit therefor, of a floor selector switch including a plurality of series of contacts arranged in said circuit, a movable contact carrying member arranged between said contacts, means normally holding the contacts on said movable member in engagement with one series of the stationary contacts to close the circuit and operate said door, actuating mechanism to close the door, and manually controlled electrically operated means carried by the elevator car to move said movable member and engage the contacts thereon with the other series of contacts and reverse the operation of the actuating mechanism and open the door.

2. The combination with electrically controlled door operating mechanism and a circuit therefor cut out devices in said circuit to break the same at the end of the opening and closing movements of the door, of oppositely disposed series of stationary contacts arranged in said circuit, movable contact members arranged between said series of stationary contacts, means normally holding said movable contacts in engagement with one series of stationary contacts to close the circuit and move the elevator door to its closed position, and electrically operated, manually controlled means to engage the movable contacts with the other series of stationary contacts and reverse the operation of said door operating mechanism to move the door to its open position.

3. The combination with electrically controlled elevator door operating mechanism and a circuit therefor, cut out devices in the circuit to break the same at the end of the opening and closing movements of the door, of a floor selector switch located in said circuit comprising oppositely disposed series of stationary contacts, movable contact members arranged between said series of

4
 stationary contacts, an armature plate and connections between the same and the movable contacts, means normally holding said movable contacts in engagement with one series of stationary contacts to close said circuit for the closing movement of the door, and a manually controlled electromagnet carried by the elevator car to attract said armature plate and move the movable contacts into engagement with the other series of stationary contacts and reverse the operation of said door operating mechanism to open the door.

5. The combination with electrically controlled elevator door operating mechanism and an electric circuit therefor, cut out devices in the circuit to break the same at the end of the opening and closing movements of the door, of a floor selector switch including oppositely disposed series of contacts located in the operating circuit, a shaft, a contact carrying arm fixed to said shaft and disposed between said spaced series of contacts, an armature plate mounted upon the 15 arm, means normally holding the contacts on said arm in engagement with one series of stationary contacts to close the electric circuit for the closing movement of the door, and a manually controlled electromagnet carried by the elevator car to attract the armature plate and move the arm to engage the contacts thereon with the other series of stationary contacts and reverse the operation of the door operating mechanism to open the door.

6. The combination with electrically controlled elevator door operating mechanism, and a circuit therefor, cut out devices in said circuit, of spaced series of contacts 20 wired in the circuit with said cut out devices, an armature plate, movable contact members connected to said armature plate, and disposed between the spaced series of stationary contacts, means yieldingly holding said movable contacts in engagement with one series of the stationary contacts to close the circuit for the closing movement of the elevator door, and manually controlled electromagnet carried by the elevator car to attract the armature plate and move the movable contacts into engagement with the other series of stationary contacts to reverse the operation of the door operating mechanism and move the door to its open 25 position.

7. The combination with electrically controlled elevator door operating mechanism, and a circuit therefor, cut out devices in said circuit, of spaced series of contacts 30 wired in the circuit with said cut out devices, an armature plate, movable contact members connected to said armature plate and disposed between the spaced series of stationary contacts, means yieldingly holding said movable contacts in engagement

35 with one series of the stationary contacts to close the circuit for the closing movement of the elevator door, an electromagnet carried by the elevator car to attract the armature plate and move the movable contacts 40 into engagement with the other series of stationary contacts to reverse the operation of the door operating mechanism and move the door to its open position, and an adjustable abutment to limit the movement of the 45 armature plate toward the magnet.

8. The combination with electrically controlled elevator door operating mechanism and a circuit therefor, of cut out devices in the circuit to break the same at the end of 50 the opening and closing movements of the door, of a floor selector switch comprising a plurality of series of stationary contacts, a rocker arm extending between said series of contacts, spaced contact members on the 55 rocker arm, a spring acting against said arm to normally hold said contact members in engagement with one series of stationary contacts and close the circuit for the closing movement of the elevator door, and manually controlled electrically operated means for rocking said arm when the elevator car is stopped at the floor landing to engage the contacts thereon with the other series of 60 stationary contacts and reverse the operation of said mechanism to move the door to its open position.

9. The combination with electrically controlled elevator door operating mechanism and a circuit therefor, of cut out devices in the circuit to break the same at the end of 65 the opening and closing movements of the door, of a floor selector switch comprising oppositely disposed series of stationary contacts, a rocker arm extending between said 70 series of contacts, spaced contact members on the rocker arm, a spring acting against said arm to normally hold said contact members in engagement with one series of stationary contacts and close the circuit for the closing movement of the elevator door, an armature plate, connecting means between said plate and the rocker arm, and manually controlled electromagnet carried 75 by the car to attract the armature plate and move the arm to engage the contacts carried thereby with the other series of stationary contacts to reverse the door operating mechanism and move the door to its open position.

10. The combination with electrically controlled elevator door operating mechanism and a circuit therefor, cut out devices in said circuit, of a floor selector switch comprising oppositely disposed series of stationary contacts located in the operating circuit, a rock 80 shaft, an arm fixed to said shaft, contacts carried by said arm to normally engage with one series of the stationary contacts to close the circuit for the closing movement of the door, an armature plate, links connecting 85

- said plate to said shaft, and an electromagnet carried by the car to attract the armature plate and move the contacts on said arm in engagement with the other series of stationary contacts to reverse said door operating mechanism and move the door to its open position.
10. The combination with electrically controlled elevator door operating mechanism and a circuit therefor, cut out devices in said circuit, of a floor selector switch comprising oppositely disposed series of stationary contacts located in the operating circuit, a rock shaft, an arm fixed to said shaft, contacts carried by said arm to normally engage with one series of the stationary contacts to close the circuit for the closing movement of the door, an armature plate, links connecting said plate to said shaft, an electromagnet carried by the car to attract the armature plate and move the contacts on said arm in engagement with the other series of stationary contacts to reverse said door operating mechanism and move the door to its open position, and an abutment for limiting the movement of said armature plate.
11. The combination with electrically controlled elevator door operating mechanism, and a circuit therefor, of a floor selector switch comprising a supporting arm, spaced series of stationary contacts mounted upon said arm and wired in the operating circuit, parallel rock shafts mounted in said arm, movable contact members mounted upon one of said shafts and disposed between the series of stationary contacts, means normally holding said movable members in engagement with one series of stationary contacts to close the circuit for movement of the door to its closed position, an armature plate, links connecting the said plate to the rock shafts, and an electromagnet mounted upon the elevator car to attract said armature plate and move the movable contacts into engagement with the other series of stationary contacts to reverse the door operating means and move the door to its open position.
12. The combination with electrically controlled elevator door operating mechanism, and a circuit therefor, of a floor selector switch comprising a supporting arm, spaced series of stationary contacts mounted upon
- said arm and wired in the operating circuit, parallel rock shafts mounted in said arm, movable contact members mounted upon one of said shafts and disposed between the series of stationary contacts, means normally holding said movable members in engagement with one series of stationary contacts to close the circuit for movement of the door to its closed position, an armature plate, links connecting the said plate to the rock shafts, and an electromagnet mounted upon the elevator car to attract said armature plate and move the movable contacts into engagement with the other series of stationary contacts to reverse the door operating means and move the door to its open position.
13. The combination with motor actuated elevator door operating mechanism, and a circuit therefor, a floor selector switch in said circuit including an armature plate, of an electromagnet carried by the elevator car to coöperate with the armature of said switch plate and close the circuit through the motor to open the elevator door, a circuit for the electromagnet, a car controller, and an operator's switch the movable element of which is the lever of the car controller.
14. The combination with motor actuated elevator door operating mechanism, and a circuit therefor, a floor selector switch in said circuit including an armature plate, of an electromagnet carried by the elevator car to coöperate with the armature plate of said switch and close the circuit through the motor to open the elevator door, a circuit for the electromagnet, a car controller, an operator's switch comprising stationary and movable contacts arranged in the magnet circuit, a manually operated handle mounted upon the car controller and movable with relation thereto, and means movable with said handle to close the magnet circuit.
- In testimony whereof I hereunto affix my signature in the presence of two witnesses.
- HOOD PITTS.
